UNITED STATES PATENT OFFICE.

WILLIAM H. REDINGTON, OF CHICAGO, ILLINOIS.

PASTE-BRUSH.

SPECIFICATION forming part of Letters Patent No. 654,414, dated July 24, 1900.

Application filed December 4, 1899. Serial No. 739,216. (No model.)

To all whom it may concern:

Be it known that I, WILLIAM H. REDINGTON, a citizen of the United States, residing at Chicago, in the county of Cook and State 5 of Illinois, have invented a certain new and useful Improvement in Paste-Brushes, of which the following is a specification.

The object of my invention is to make a simple, economical, and efficient flat brush especially adapted to the use of mucilage or 10 paste, but also applicable to other purposes; and the invention consists in the features and combinations hereinafter described and claimed.

15 In the accompanying drawings, Figure 1 is a side elevation of my improved brush when used as a paste-brush; Fig. 2, a cross-section of the brush-holding ferrule before the insertion of the brushes; Fig. 3, a cross-section of 20 the same with the tubes swaged inwardly to hold the individual brushes; Fig. 4, an enlarged sectional elevation of the brush-holding ferrule and a portion of the fountain; Fig. 5, a modified form of brush, and Fig. 6 25 a side elevation of a brush adapted for ordinary uses or purposes.

In constructing a paste or mucilage brush in accordance with my improvements and using it in connection with a fountain or collapsible tube A, having a screw-cap or ferrule B, I form the ferrule of soft yielding metal, such as lead or zinc, having at least 30 two spaces b therein, in which small bunches of bristles or individual brushes C C' can be inserted. As shown in Fig. 2, the ferrule in its original state is formed with round or cylindrical openings, in which the bunch of bristles may be inserted. It is afterward 35 swaged or collapsed, so as to form the shapes shown in Fig. 3 and grip the bristles firmly 40 in position. From this arrangement it will be seen that the brush is arranged in the form of a flat brush made up of a gang of two or more smaller brushes without the use of the 45 objectionable rivets.

It is desirable and, indeed, oftentimes necessary in the use of paste or mucilage that a supply be furnished to the brushes in as simple and efficient a manner as possible. In 50 order to accomplish this result, I provide the ferrule or cap, as the case may be, with a tube D, extending in the same vertical plane as

the bristles, but between each pair of bristles, so that a supply of liquid paste or mucilage can be easily furnished merely by collapsing 55 the tube or inverting the fountain, as the case may be.

Where the brush is composed of more than two brushes, a supply-tube extending between each pair and connecting with a main 60 supply-tube, should be provided, as shown in Fig. 5. In this figure I have shown the collapsible tube A as provided with a ferrule-cap E, containing a brush formed of a gang of five small brushes e. There are four supply-tubes e', one between each pair of brushes 65 and connected with a main supply-channel e'', leading to and having connection with the fountain in the collapsible tube.

As far as described my improvement in 70 brushes is set forth as applied to a paste or mucilage brush having a fountain supply tube or head; but, as shown in Fig. 6, the form of brush composed of two or more smaller brushes producing a flat brush and dispensing 75 with rivets for securing or attaching the bristle or brush portion to its head or back is applicable to brushes for other uses and purposes without a supply-fountain and delivery tubes. The mode of attaching the bristle or 80 brush portion to a head or back can also be used with other forms of brushes than flat ones. It will therefore be understood that I contemplate using my invention in any and all forms of brushes to which it may be found 85 applicable.

The principal advantages arising from the use of a brush constructed as above described are its simplicity and economy of manufacture. 90

I claim—

1. In a flat brush, a handle formed of a collapsible tube, a head on the handle having an interior chamber with a delivery opening or openings leading therefrom, and a number of flat brushes secured in the head of the handle side by side adjacent to the opening or openings therein, whereby collapsing the handle supplies the contents thereof to the chamber for delivery to the brushes, substantially as 95 described.

2. The combination in a flat brush of a number of smaller brushes, carried by a common head side by side in the same longitudinal

- plane, a series of clasps or sockets corresponding in number to the number of smaller brushes and forming as a whole the head, and made from soft metal to have the bristles of each smaller brush entered into a clasp or socket and held therein by flattening the clasp or socket to spread the bristles, and a discharge-tube between the adjacent smaller brushes for supplying mucilage or paste to the brush as a whole from the interior of the head, substantially as described.
3. The combination in a flat brush of a number of smaller brushes carried by a common head side by side in the same longitudinal plane, a common head, a chamber in the head, a series of clasps or sockets corresponding in

number to the number of smaller brushes and formed with the head of soft metal, for each small brush and having its bristles entered into a clasp or socket and held therein by flattening the clasp or socket to spread the bristles, a discharge-tube between each pair of small brushes leading from the chamber of the head, and a collapsible tube containing mucilage or paste connected with the head for supplying mucilage or paste to the brush as a whole through the discharge-tubes, substantially as described. 20 25
